SELECTIVE SIGNALING SYSTEM

Abraham S. Benjamin, Chicago, Ill., assignor to
 Teletype Corporation, Chicago, Ill., a corpora-
 tion of Delaware

Application February 7, 1934, Serial No. 710,107

7 Claims. (Cl. 177—352)

This invention pertains to signaling systems and more particularly to composite fire alarm and printing telegraph systems arranged to permit transmission to a plurality of stations simultaneously.

The principal object of the invention is the provision of a signaling system including a central or control station and a plurality of distant stations arranged so that the control station may communicate telegraphically or through the operation of audible signaling apparatus with all of the stations or with any group of the stations.

Another object is to provide for dividing the distant stations into groups so that one or more groups of stations may be selected to receive a message and other groups excluded from such message.

The above and other objects of the invention are attained by connecting a plurality of stations together in groups by a line wire and then extending that line wire to a central office and proceeding thus until all stations are connected in several such groups. At the central office, each line wire has a switch by which one group or 20 more or all groups may be connected to a transmitter which will transmit upon the selected line wires the signals suitable for the message to be transmitted. Thus a selectivity in type of signals is employed to enable the operator at the central 25 office to send electrical signals of different kinds to operate at the stations electrical receiving devices of different classes, the equipment at the stations being such that each station is equipped with a plurality of different types of signal receiving devices and the devices are so associated 30 that any signal device may be operated independently of all other signal devices at that station.

The apparatus at each station comprises an 35 audible signal device or a plurality of such devices and also a printing telegraph receiving device. These several receiving devices are associated with the line wire by means responsive selectively to signals in the line such that only one receiving 40 device will respond to any signals sent from the control office.

At the central control office a signal transmitting device for each type of signal to be transmitted is provided, and switches are arranged to 45 permit any transmitting device to be connected to any line or to any group of lines at one time.

A better understanding of the invention may be had from the following description, taken in conjunction with the accompanying drawing, wherein 50 Fig. 1 shows line circuits with stations indi-

cated and with details of central office control apparatus, and

Fig. 2 shows details of a station.

Printing telegraph transmitting equipment is provided which may broadcast by suitable currents to the stations in groups, and manual impulsive keys are provided which will supply to the stations signal impulses of certain current strength for operating either of two signal bells according to the polarity of the applied current. 10 Switches are arranged for transferring signal lines from the printing service to the bell operating service and vice versa.

A control circuit for printing telegraph signals comprises telegraph transmitter 1, telegraph printer 2, and transmitting relays 3, 4, and 5, whose contacts and armatures are connected through contacts of keys 6, 7, and 8 to lines 9, 10, and 11 which have each a plurality of stations 12. Any key may be operated to transfer its associated line from the printing telegraph control circuit to the bell control key 13 and any or all keys 6, 7, 8, may be operated at one time.

Each station 12 has circuits and apparatus as shown in Fig. 2 in which three line relays are connected in the circuit of the signaling line. Relay 14 responds to polar signals and has two contacts 15 and 16 and a tongue 17 which is normally held out of contact with either contact by a centering spring 18. Relay 14 is marginal and will operate only when supplied with a current of 50 milliamperes or more and responds selectively to polar currents either to close tongue 17 to contact 15 to operate bell 19 by current from battery 20, or to close tongue 17 to contact 16 to operate bell 21 by current from battery 20.

Relay 22 is polar and is sensitive to currents of value less than 50 milliamperes, and by its contact it controls the operation of a telegraphic receiving printer 23 by current from battery 24.

Relay 25 is marginal and responds whenever relay 14 responds to current in the signaling line. The function of relay 25 is to prevent the operation of the receiving printer 23 upon signals which operate relay 14 and which also operate relay 22. 45 This function is effected by providing the armature of relay 25 with a contact to operate a slow-to-release relay 26 which by a cascade circuit operates a slow-to-release relay 27 which short circuits contacts of relay 22 and closes the circuit 50 of receiving printer 23 so that it will be unresponsive to control by relay 22.

Station 12 therefore requires a strong positive current to operate relay 14 to operate bell 19, a strong negative current to operate relay 14 to 55

operate bell 21, and at other times it requires weaker currents, both positive and negative, in properly timed signals to operate relay 22 to control the receiving printer 23. These several currents may be supplied by controlling mechanism at the central office, Fig. 1.

Keys 6, 7, and 8 are shown set for connection of lines 9, 10, and 11 to contacts of relays 3, 4, and 5, and the system thus is shown in condition 10 for transmission of printing telegraph signals. Operation of transmitter 1 causes code signals upon relays 3, 4, and 5, and each such operation causes a reversal of current in lines 9, 10, and 11. With relay 3 energized as shown, current from 15 battery 30 flows through wire 31, resistor 32, front contact and armature 33, wire 34, inner contact and switch spring 35, line wire 9 and stations 12, switch spring 36 and inner contact, wire 37, armature 38 and front contact, resistor 39, 20 and wire 40. When relay 3 is deenergized for a spacing signal, current flows from positive pole of battery 30, through wire 31, resistor 32, back contact and armature 38, wire 37, inner contact and switch spring 36, line wire 9 and stations 12, 25 switch spring 35 and contact, wire 34, armature 33 and back contact, resistor 39, and wire 40. The polar direction of the current through line wire 9 is reversed by operation of relay 3 and transmitter 1 and relay 3 thus controls polar relays 22 30 at all stations 12 in line 9, signals being repeated in a local circuit containing battery 24 and receiving printer 23 and thus recording upon receiving printer 23 all messages generated by transmitter 1 at the central office.

35 Key 6 when operated to its alternative position, connects its springs 35 and 36 to outer contacts and provides a circuit for operation of manual impulsing key 13. When key 13 is operated downwardly, it engages its lower contact 41 and closes a circuit for current from negative battery 42 through contact 41, key 13, wire 43, resistor 44, outer contact and switch spring 35, line 9 and stations 12, operated switch spring 36 and outer contact, resistor 45, and wire 46 to battery 42. 40 Alternatively, when key 13 is operated upwardly it engages its upper contact 47 and provides a circuit for current from positive battery 48 through contact 47, key 13, wire 43, resistor 44, outer contact and switch spring 35, line 9 and stations 12, operated switch spring 36 and outer contact, resistor 45, and wire 46 to battery 48.

The operation of key 13 into engagement with its contact 41 provides current from negative battery 42 of sufficient strength to operate station 55 relays 14, 22, and 25, under which conditions relay 14 operates to engage its contact 16 and thus to operate the signal device 21, relay 25 operates to energize relays 26 and 27 to control the local circuit of receiving printer 23, and relay 22 operates ineffectively because the circuit of receiving printer 23 has been closed at relay 27. Thus, in response to key 13 in engagement with its contact 41, signal device 19 is not operated because tongue 17 moves away from contact 16, receiving printer 23 is not operated because its circuit is controlled by relay 27, and signal device 21 is operated solely because tongue 17 is moved against contact 16. Alternatively, when the key 13 is operated to engage its contact 47, positive current is supplied by battery 48 to stations 12 of sufficient strength to operate relay 14 to engage its contact 15, relay 25 is operated to energize relays 26 and 27, and relay 22 is not operated or is operated to 70 close its contact because of the direction or 75

polarity of the applied current. Thus signal device 19 will be operated solely.

With key 6 in position as shown in the figure, operation of the transmitter 1 will provide in line 9 signaling currents of sufficient volume to 5 operate relay 22 at each station and of volume insufficient to operate relays 14 and 25 so that with relay 14 unoperated, signal devices 19 and 21 will be unoperated and receiving printer 23 will be operated through a local circuit including 10 receiving printer 23, battery 24, and contacts of line relay 22, under control of transmitter 1 at the central office.

As is evident from Fig. 1, the stations 12 on the line conductors 10 and 11 may be associated 15 with the respective transmitters through the operation of keys 7 and 8. Thus the stations may be selectively connected into groups.

The invention has been described with reference to a specific system of switches and circuits 20 designed to illustrate the principles of the invention, but its utility is not limited by the specific form shown, being limited only by the scope of the appended claims.

What is claimed is:

1. In a signaling system, a single line circuit, a station having a polar relay in series with said line circuit operable on current of a predetermined strength, a polar relay connected in series with the first mentioned polar relay operable on 30 current of lesser strength, and means operable on the same current strength as the first mentioned polar relay for rendering the second mentioned polar relay ineffective.

2. In a signaling system, a single line circuit, a 35 station having a plurality of signaling devices, means in said line circuit operable on current of a predetermined strength for controlling certain of said signaling devices selectively, a polar relay connected in series with said means and operable on a lesser current for controlling a signaling device, and means operable on the same current strength as the first mentioned means for disabling the signaling device controlled by the polar relay.

3. In a signaling system, a single line circuit, a station having a plurality of signaling devices, means in said line circuit operable on current of a predetermined strength for controlling certain of said signaling devices selectively, means connected in series with the first mentioned means and operable on a lesser current for controlling a signaling device, and means in series with the first and second mentioned means and operable upon the same current strength as the first mentioned means for disabling the signaling device controlled by the second mentioned means.

4. In a signaling system, a line conductor extending to a station, two normally open local circuits, a polar relay at said station responsive 60 to currents of a predetermined value for controlling said circuits selectively, two audible signal producing devices, one in each of said circuits, a recording device at said station responsive to currents of a value lower than said predetermined 65 value, and means at said station operating in response to currents of said predetermined value only to disable said recording device, said polar relay, recording device and disabling device being connected in series.

5. In a signaling system, a single line circuit, a station having a polar relay in series with said line circuit operable on current of a predetermined intensity, a polar relay connected in series with the first mentioned polar relay operable on 75

current of lesser intensity, a non-polar relay operable on the same current intensity as the first mentioned polar relay for controlling the effectiveness of the second mentioned polar relay, and means whereby said non-polar relay is energized simultaneously with said polar relays.

6. In a signaling system, a single line circuit, a station having a polar relay in series with said line circuit operable on current of a predetermined intensity, a polar relay connected in series with the first mentioned polar relay operable on current of lesser intensity, a non-polar relay in series with said line circuit operable on current of said predetermined intensity, and means controlled by said non-polar relay for rendering the second mentioned polar relay ineffective.

7. In a signaling system, a single line circuit in-

cluding a polar relay operable on current of a predetermined intensity, a polar relay operable on current of lesser intensity, and a non-polar relay operable on the same current intensity as the first mentioned polar relay, armatures operable by each of said relays, a plurality of circuits selectively closable by the armature of the first mentioned relay, a signal producing device in each of said circuits, a circuit closable by the armature of the second mentioned polar relay, a signal recording device in said circuit, a cascade circuit closable by the armature of the non-polar relay, a shunt circuit across the armature of the second mentioned polar relay, and means controlled by the cascade circuit for closing the shunt circuit.
